FLEXIBLE ARTIFICIAL FISHING LURE

Carl R. Cordell, Jr., P.O. Box 2020,
Hot Springs, Ark. 71901

Filed May 31, 1972, Ser. No. 258,482

Term of patent 14 years

Int. Cl. D22—05

U.S. Cl. D22—27

FIG. 1 is a side elevational view of my flexible artificial fishing lure; the other side elevation being a mirror image thereof;

FIG. 2 is a top plan view thereof;

FIG. 3 is an end elevational view taken from the left of FIG. 2; and

FIG. 4 is an end elevational view taken from the right of FIG. 2.

I claim:

The ornamental design for a flexible artificial fishing lure, as shown and described.
